INSULATED CLAMP

Robert S. Deal, Los Altos, Calif., assignor to Raychem Corporation, Redwood City, Calif., a corporation of California

Filed July 25, 1960, Ser. No. 45,061
3 Claims. (Cl. 174—49)

This invention relates to clamping devices and has particular reference to an electrically insulated clamp for supporting electrical cables, wire bundles and the like.

A primary object of the present invention is to provide a novel clamping device provided with insulation means.

A further object of the present invention is to provide a novel clamp formed from a single length of insulation-covered metal.

Another object of the present invention is to provide a novel process for forming an insulated clamp.

Other objects and advantages of this invention it is believed will be readily apparent from the following detailed description of a preferred embodiment thereof when read in connection with the accompanying drawings.

In the drawings:

FIGURE 1 is a fragmentary perspective view of the blank from which the clamp of the present invention is fabricated.

FIGURE 2 is a side view of the clamp of the present invention illustrating the clamp in the open position.

FIGURE 3 is a view similar to FIGURE 2, but illustrating the clamp in the closed, installed position.

Referring now to the drawings, the clamp 10 of the present invention comprises essentially a single, rectangular strip 11 of relatively thin metal encased in a sleeve or jacket 12 of insulation material. The strip 11 has a generally circular or cylindrical body portion, provided at one extremity with an outwardly off-set portion 13 leading to an L-shaped portion 14. The other extremity is provided with a mating L-shaped portion 15, the outer, parallel legs 20 and 21 of the respective L-shaped portions are joined to the body portion by connecting legs and are provided with apertures 22 and 23 for the reception of a bolt element 24 whereby the clamp may be secured to a wall 30 or other flat surface for supporting a bundle of wires (indicated by the phantom lines of FIGURE 3), or other objects. It will be seen that by virtue of the shape of the clamp, the body portion will, when in the closed position of FIGURE 3, form a virtually unbroken closed circle or cylindrical inner surface.

As indicated in FIGURE 1, the clamp is initially in the form of a flat metal rectangle or strap having applied thereto the insulation jacket 12. The jacket is tightly affixed to the strap by inserting the strap inside a suitable length of a sleeve of a heat-unstable plastic material, i.e., a material which has been pre-expanded under condition such that it will shrink to its original diameter upon the application of heat. Thus, after insertion of the strap into the sleeve, which has an expanded diameter approximately equal to the width of the strap and an original diameter less than the cross-sectional perimeter of the strap, the assembly is heated to the shrink-back temperature and the sleeve shrinks tightly onto the strap, forming the jacket 12.

The sleeve which ultimately forms the jacket 12 can be made from any plastic material having plastic memory properties. A process for producing such sleeving or tubing from polytetrafluoroethylene and irradiated or

2

chemically cross linked polymers such as polyethylene, etc., is disclosed in the copending application of Cook et al., Serial No. 43,230, filed July 15, 1960 now Pat. No. 3,086,242 on "Process and Apparatus for Producing Materials Having Plastic Memory." While such materials are preferred, other materials such as expanded vinyl plastic and various elastomers such as silicone rubber, neoprene rubber, etc., dipped or stretched onto the strip, can be used.

The insulated strip illustrated in FIGURE 1 is readily formed, as in a punch press die, into the shape illustrated in FIGURE 2. As indicated above, the closed shape shown in FIGURE 3 is almost a perfect circle. In the use of the clamp in supporting wire bundles, the design of the L-shaped portion 15 functions as a wedge in pushing the wire bundle into the minimum circular area and eliminating pinching of the individual wires as the clamp is closed down. The clamp thus provides a strong, insulated structure capable of securing heavy objects to flat surfaces and yet so designated as to be inexpensive to manufacture and not subject to damage in normal handling and use.

Having fully described my invention, it is to be understood that I do not wish to be limited to the details set forth, but my invention is of the full scope of the appended claims.

I claim:

1. An insulated clamp comprising a strip of metal having tightly applied thereto a heat-shrunk sleeve of a heat-unstable plastic material, said clamp having a body portion and extremities, each of said extremities being generally L-shaped with an outer leg and a connecting leg joining said outer leg to said body portion, said extremities being relatively oriented for nesting thereof in clamping relationship, said connecting legs extending in a direction outwardly and away from the periphery of said body portion, a first one of said connecting legs being generally tangent to the periphery of said body portion, said connecting legs being substantially parallel and said outer legs being substantially parallel when said extremities are in clamping relationship, said first connecting leg being connected to said body portion at a first point and the second of said connecting legs being connected to said body portion at a second point, said first point and said second point being adjacent to each other when said extremities are in clamping relationship, said body portion forming a substantially circular shape when said first point is brought adjacent to said second point by placing said extremities in clamping relationship and said extremities being adapted to be secured to each other while in clamping relationship.

2. The clamp of claim 1 wherein the outer leg connected to said second connecting leg is generally tangent to the periphery of said body portion.

3. The clamp of claim 1 wherein said first connecting leg is connected to said body portion by an offset portion.
